DRYING APPARATUS

Thomas G. Johnson, Cloquet, Minn., assignor to
The Northwest Paper Company, Cloquet, Minn.,
a corporation of Minnesota

Application November 24, 1930, Serial No. 497,702

3 Claims. (Cl. 34—48)

The present invention relates to dryers, especially for paper machines.

Between drum dryers of paper making machines, particularly in those portions where fabric, known as a felt, travels with the paper, there are formed elongated pockets of rather limited cross-sectional area between the felt and the paper and rolls. Both the felt and the paper are thus exposed for evaporation of water or moisture. Because of the elongated and sometimes tubular nature of these pockets the normal circulation of air is poor and drying is irregular and not uniform across the widths of the felt and of the paper web. This results in uneven tension in both felt and web. The unequalized conditions of drying in both cases affect the uniformity of quality in the paper. They also affect the life of the felt and render it non-uniform in character across its width because of continued use with different degrees of moisture content.

The present invention aims to increase the rate of evaporation of a paper drying machine and to render the drying more uniform along the width of the paper web and the felt.

Another object is to prolong the life of the felts by uniformly decreasing the moisture content thereof in use.

Still another object of the invention is to increase the production of a paper machine occasioned by the improved drying.

A further object of the invention is the provision of means to admit moisture-absorbing air into the pockets, to admit the air with a gentle flow, and to use warm, waste air from around the paper machine which air is further heated to increase its moisture absorbing capacity.

It is a particular object of the invention to admit the air into the pockets in such a regulated manner that the air discharged from the pockets is substantially saturated at the temperature of discharge, thereby approaching the goal of maximum efficiency in the use of heat units.

Various other objects and advantages of the invention are contemplated and will be apparent from the following description of the invention as it is applied to a known type of paper machine, shown in the accompanying drawings, in which:

Fig. 1 is a diagrammatic view in elevation of a section of a paper machine.

Fig. 2 is a diagrammatic view of the air feeding system of the invention.

Fig. 3 is an end view of the paper machine section of Fig. 1 showing also an end view of the air-feeding system.

One feature of the invention is the use of warm, waste air. It is well known that the capacity of air to absorb moisture is greater, the higher its temperature. This is readily illustrated from the data of the following table:

Table 1

Temperature C	Grams moisture per cubic meter of saturated air	Increased capacity per 10° C.
0	4.8763	
10	9.3717	4.4954
20	17.1768	7.8051
30	30.1293	12.9525

In the present invention I aim to utilize waste, warm, moist air which may be collected from around the paper machine, rather than cooler and dryer air such as may be taken from out-of-doors. I heat this air and thus raise its capacity to absorb moisture. The air wasted from the pockets of the machine will be at a high temperature and may be near the temperature of steam. All the heat units in this wasted air may be considered as lost in ordinary practice.

In this invention I re-use much of this air and hence effect a saving in heat units. Although I use preheated air, it is so gently introduced that it becomes further heated in the pockets and thereby has its capacity to hold moisture further increased.

In consequence I attempt to regulate the temperature, the moisture and the rate of use, so that the air discharged from the pockets is substantially saturated.

The air which leaves the ends of the pockets circulates and mingles with air circulating through the machine. A good portion of this air usually leaves directly through hoods provided to carry off the moist air and the rest of

it mingles with the air in the room. A portion drops into the pit under the machine.

In the accompanying drawings I have illustrated a paper machine by taking one section 5 thereof as typical of the several features of the present invention, and it will be readily understood how the entire machine may embody duplicating parts of the invention.

A length of machine is selected at the center 10 of which there is a division into forward and rearward drying sections. The important distinction appearing herein is the use of different felts for the two sections. There are one series of drying rolls 10 in one section and another series 11 in the other section. The frame of the machine is omitted in order to make clearer the constructions involving the invention.

The upper rolls of the series 10 have a felt 12 which holds a paper web 13 to the rolls, the 20 lower stretch of the felt being looped over idlers 14 between the rolls. An upper stretch 15 on idlers 16 completes the endless loop of felt 12. The lower rolls of series 10 have a similarly arranged endless felt 17, idlers 18 between the rolls, 25 a return stretch 19 and idlers 20 therefor. The other series of rolls 11 has a similar construction with upper felt 21 and lower felt 22.

The felts, the web and the rolls and the idlers 30 all combine in various ways to form long or tubular pockets. Ordinarily the air stagnates locally in the pockets and is hot and saturated. This reduces the effective drying area, delays the completion of the process, and causes non-uniform drying across the width of sheets. Into 35 the pockets I project air lines, at various and adjustable depths in the pocket, and I provide means for supplying pre-conditioned air to said lines.

As a source of air I prefer the warm moist air 40 found in the machine pit. Beneath the level of the lower rolls 10 and 11 and above the floor 23, at one side of the machine is a flared air intake 24 (Figs. 2 and 3) connected by an elbow 25 to a blower 26, operated by pulley 27. A conduit 45 leaves the blower and branches out to various parts of the machine. It comprises a riser 28 extending to a point above the rolls 10 and 11, parallel feeders 29 and 30 along the two sides of the machine, a cross-connection 31 in one 50 feeder, a T-connection 32 in the other feeder, a connecting length 33 from the cross-connection to the T-connection, and a horizontal feeder 34 from the cross-connection to the riser.

Means is provided to heat the air and I prefer to use lengths of steam pipe within the overhead air feeding system. I provide a single steam line throughout the whole feeding system. A valved steam line 35 enters the overhead system and follows the branches as indicated by dotted 55 lines and arrows in Fig. 2 returning parallel to itself in each part of the conduit system. It emerges at 36 and at the end is provided with a steam trap 37. By this system air can be heated quickly without the necessity of circulation, or forcing heated air from one place to another. Hot air is on tap.

From each length of feeders 29 and 30 are depending valved lengths of pipe 38 tapped into the feeders, as shown in Figs. 1 and 3. Some 70 extend to the level of the lower pockets. Others extend only to certain high pockets, such as lengths designated 40 and 41. The nozzles may be placed at any location where they are desirable, and this may be varied according to conditions. Ordinarily, a large number are provided

and are operated as conditions may require. Each one has a length of pipe 43 entering a pocket to a point where it is particularly desirable to increase the drying. There may be either one or two in a pocket, and one or both may be operated. I prefer to make the horizontal length 43 adjustable, either by utilizing different lengths of pipe, or by using a telescoping construction whereby one pipe 44 slips over pipe 43.

In order to protect the paper and the felt from 80 injury by dirt accidentally emerging from the air-system, I may provide a screen filter 45 on the ends of the pipes.

In operation of the system air is gently introduced from the air system into the pockets. High 85 pressure is not employed. Only sufficient air is required to insure circulation of air through the pockets. The normal condition of the air in the pockets is one of practical saturation and high 90 temperature. The normal condition of air in the air system may be moist but not saturated at an elevated temperature which may be lower than the temperature of air in the pockets. This heated moist non-saturated air replaces the 95 saturated air and itself approaches substantial 100 saturation as it leaves the pocket.

One feature of the invention is the use of heated, waste, non-saturated air at an elevated 105 temperature to induce circulation through the pockets and to induce uniform drying in pockets. Very little heat is required to preheat the air in the system as compared with air taken from out-of-doors. Because the air is heated and later becomes practically saturated, there results a higher efficiency in use of heat units in 110 operating the paper machine.

The invention permits an operator to observe 115 the paper and felts and where he finds a region drying slower than other regions, he may increase or localize the supply of air to cure the difficulty. By providing the valved lines 38 and telescopic 120 lengths, adjustments may be made for peculiarities of machines and conditions of operation.

I have found that with the system here described I have been able to operate the drying 125 drums at a steam pressure of five pounds per sq. in. as compared to a pressure of eighteen pounds which is otherwise necessary. In addition to this reduction in temperature of the dryers I have been able to increase production of the machine 130 10%, produce a paper of uniformly high moisture content, a paper which is evenly dried across the machine, and have been able to more than double the life of the dryer felts.

I claim:

1. A drying system for a paper making machine comprising in combination with a paper-making machine having pockets therein, a source of warm waste air, an air distributing conduit 135 extending along the length of the machine, means to collect and force said air through said conduit, a steam line coextensive with said conduit to heat the air therein, and discharge lines connected with said conduit for discharge of the heated air into pockets of the paper machine. 140

2. A drying device for a paper making machine comprising in combination with a paper-making machine having an elongated pocket therein formed by rolls and travelling sheets, an air-discharge line projecting at a depth into said pocket, 145 said line having a telescopic structure permitting placement of the inner end of said line at a pre-determined region in the pocket, and means to supply a drying air to said line. 150

3. A drying system using air for travelling sheets in a paper machine having pockets formed in part by said sheet, comprising in combination with the paper machine, an air-feeding conduit 5 extending along the length of the machine, means to supply air to said conduit, air intake means located in the pit of the machine to draw air therefrom, means coextensive with said conduit to heat and maintain hot the air in said conduit, and a series of discharge pipe lines from said feeder conduit each extending to a depth into the pockets of the paper machine. 80
